UNITED STATES PATENT OFFICE.

JARED MARIS, OF COLUMBUS, OHIO.

DESIGN FOR THE ORNAMENTATION OF FLANGES FOR HUBS.

SPECIFICATION forming part of Design No. 16,431, dated December 29, 1885.

Application filed October 30, 1885. Serial No. 181,431. Term of patent 14 years.

To all whom it may concern:

Be it known that I, JARED MARIS, a citizen of the United States, residing at Columbus, in the county of Franklin and State of Ohio, have 5 invented and produced a new and original Design for Flanges for Wheel-Hubs, of which the following is a specification, reference being had to the accompanying drawing.

My invention relates to a design for the ornamentation of the flange of a wheel-hub; and it consists in a continuous series of plane surfaces on the periphery of the flange, whereby the periphery or flange, instead of being circular, is made up of a continuous series of 15 angles.

The accompanying drawing represents a flanged shell band embodying my design.

A represents a flanged band having a con-

tinuous series of short plane surfaces, *a*, on the periphery of the flange thereof. These plane 20 surfaces are of a length sufficient to give to the periphery of the flange an angular appearance.

Having fully described my invention, what I claim as new, and desire to secure by Letters 25 Patent, is—

In a design for the flanges of a wheel-hub, the ornamentation of the same, consisting of a continuous series of plane surfaces, substantially as described, on the periphery of the 30 flange.

JARED MARIS.
